UNITED STATES PATENT OFFICE.

RAFAEL M. ROBLES, OF MANILA, PHILIPPINE ISLANDS.

CALIPERS.

Application filed January 2, 1923. Serial No. 610,253.

To all whom it may concern:

Be it known that I, RAFAEL M. ROBLES, citizen of the Philippine Islands, residing at Manila, Philippine Islands, have invented 60
5 new and useful Improvements in Calipers, of which the following is a specification.

This invention relates to calipers and resides in the provision of a device including pivoted members so arranged that one end 10 of the device is adapted for use with outside work, and the other end adapted for inside work, said members being simultaneously movable initially, and the members used for inside work being susceptible of 15 subsequent independent movement to obtain the necessary difference between the inside and outside measurements.

The nature and advantages of the invention will be better understood when the following detailed description is read in connection with the accompanying drawings, the invention residing in the construction, combination, and arrangement of parts as claimed.

25 In the drawings forming part of this application, like numerals of reference indicate similar parts in the several views, and wherein:

30 Figure 1 is a view in elevation looking at one side of the caliper.

Figure 2 is an edge elevation.

Figure 3 is a view similar to Figure 1, looking at the opposite side of the caliper.

35 Figure 4 is a detail view of one of the pivoted members.

Figure 5 is a detail view of another of the pivoted members.

Figure 6 is a sectional view taken on line 6—6 of Figure 1.

40 Figure 7 is a sectional view taken on line 7—7 of Figure 2.

Figure 8 is a detail view of the adjusting means for the members for moving the latter simultaneously.

45 Figure 9 is a detail view of the remaining pivoted member of the calipers.

The calipers forming the subject matter of the present invention embodies three distinct pivoted members clearly illustrated in 50 the drawings and which members are indicated at A, B, and C respectively. These members are associated by a common pivot 10 in a manner to be hereinafter described, so that all of the members may be moved simultaneously, and certain members adjusted independently of the other members,

The construction of the calipers is such, that one end of the device is used for outside work, and the opposite end used for inside work and for this purpose, the members are so arranged that the members A and C cooperate for outside measurements while the members A and B are used together for inside measurements.

The member A includes a curved end portion 11 which projects from an intermediate body portion 12, and a straight portion 13 which extends from the opposite side of the body portion as shown. The body portion 12 has a curved edge graduated as at 14, and also provided with an opening 15 for the reception of the pivot 10. The curved end portion 11 is also provided with a slot 16 for a purpose to be hereinafter described. The member B also includes a central body portion 17 having an opening 18 for the reception of the pivot 10, and projecting from the body portion is straight leg portion 19, which is arranged normally parallel with the leg portion 13 of the member A, and cooperates therewith for obtaining inside measurements. Projecting obliquely from the body portion 17 of the member B is an extension 20 terminating in a point 21, which is adapted to move over graduations 22 provided on an extension 23 formed on the member C for a purpose to be hereinafter more fully described. It will be noted that the graduations 22 are in inches and fractions thereof and increase from "0" which is 50 arranged centrally of the extension 23 toward the opposite ends thereof. The graduations at one side of the "0" include the sign "plus" as indicated at 24, and the graduations at the opposite side include the sign "minus" indicated at 25. It will be noted that the body portion 17 of the member B is also provided with an arcuate-shaped slot 26, which coincides with a slot 27 in the body portion of the member A and 55 passed through these slots is a head pin 28.

The body portion 17 of the member B is also provided with an indicating point or character 29 which cooperates with graduations 30 provided on the opposite side of the curved edge portion of the member A. As above stated, this curved edge portion is also provided with graduations 14, so that both sides of this curved portion is graduated as illustrated in Figures 1 and 3. The indicating character 29 cooperates with the graduations 30, so that a reading may be 60 65 70 75 80 85 90 95 100 105 110

— obtained for that end of the device used for inside work.

The member C consists of a curved leg portion 31, one end of which is provided with an opening 32, to accommodate the pivot 10, which as above stated, is common to all of the members A, B and C. The member C adjacent this end carries the pin 28 which passes through the slots of the members A and B as above set forth. This end of the member C is also provided with an indicating character 33 which cooperates with the graduations 14 on the member A, so that a reading may be readily obtained for outside measurements. As above stated, the member C cooperates with the curved leg portion of the member A for outside work, and these members are moved in unison in a manner to be hereinafter described. The member C is provided with the extension 23, the latter being graduated in the manner described, and these graduations are presented to view at the same time the graduations 30 are so presented, being on the same side of the device in its entirety. This extension 23 is provided with a curved slot 34, which receives an apertured lug 35 formed on one end of a threaded element 36, this element being equipped with a nut 37 as shown.

The obliquely disposed extension 20 of the member B is provided with an opening 38 to receive the apertured lug 35, so that when the threaded element 36 is adjusted in the slot 34, the extension 20 will be correspondingly moved over the graduations 22 of the said extension 23 of the member C. To effect this adjustment, I make use of a threaded bolt 39 which operates in the apertured lug 35, this bolt having a head 40 which is provided with a groove 41 having a swiveled connection with an apertured lug 42 formed on one end of a pin 43 arranged at one end of the extension 23. The latter is provided with an opening 44 to receive the apertured lug 42. Manifestly, by turning the bolt in either direction, the extension 20 of the member B will be moved to one side or the other of the "0" forming part of the graduations on the extension 23. It is to be understood that the member B is loosely mounted on the pivot 10, so that the member may be adjusted independently of the leg 13 of the member A to obtain the necessary difference between the inside and outside measurements otherwise obtained by use of the device in its entirety, while the member B is connected in a manner just described with the member C, so that when the latter mentioned member is adjusted together with the member A, the member B is also simultaneously adjusted.

The members A and C are connected by means of a threaded element 45, which is pivoted at one end as at 46 upon the member

C, while this threaded element passes through an apertured lug 47, which slides in the arcuate-shaped slot 16 of the member A. This lug is also arranged on one end of a pin 49 which is associated with the member A as shown. A nut 50 is carried by the threaded element 45, and when this nut is actuated, the members A and C are simultaneously moved toward or away from each other, depending of course upon the direction in which the nut is turned, these members being so adjusted to determine the outside measurements of the particular article being dealt with, while at the same time, the leg portion 19 of the member B, is simultaneously moved with relation to the leg portion 13 of the member A. These leg portions are used for determining the inside measurements as above stated. The element 46 is surrounded by a coiled spring 51, which exerts a tension upon the members A and C when the latter are operated, this spring bearing against the leg 47 and against the nut 52 carried by the outer end of the element 46. When the nut 50 is turned in the proper direction to allow the members A and C to move toward each other, the spring 51 operates to close the calipers.

In practice, one end of the device is used for determining outside measurements as above described, in which instance, the indicating character 33 of the member C is used in connection with the graduations 14 of the member A, and that all of the members are simultaneously adjusted or moved incident to the operation of the nut 50. The legs 13 and 19 of the members A and B are adjusted relatively to determine the inside measurements, in which instance, the indicating character 29 is used in connection with the graduations 30 of the member A. Now, after the outside measurements of the particular article dealt with have been determined, and it is found necessary to vary the inside measurements determined by the distance between the legs 13 and 19 respectively, it is only necessary to move the extension 20 of the member B along the graduated extension 23 of the member C the requisite distance, with a consequent adjustment of the leg 19 with relation to the leg 13. If the extension 20 is moved in a direction of the sign "plus" at one side of the "0" on the extension 23, the distance between the legs 13 and 19 is increased accordingly, while, if the extension 20 is moved in a direction of the sign "minus" the distance between said legs are decreased accordingly. The calipers may be constructed from any suitable material and also vary in size without departing from the spirit of the invention, and the device is designed to permit of it being easily handled, and it also operates with absolute reliability and accuracy.

While it is believed that from the fore-

going description, the nature and advantages of the invention will be readily apparent, I desire to have it understood that I do not limit myself to what is herein shown and described, and that such changes may be resorted to when desired as fall within the scope of what is claimed.

What I claim is:—

1. A device of the character described comprising a pair of pivotally connected members, each including a curved edge portion, said legs being used together for outside measurements, one of said members including a straight leg portion, said last mentioned member having graduations on both sides thereof, the other member of said pair having indicating characters co-operating with the graduations to provide for a reading of the device, an additional member pivotally associated with the aforementioned members, and including a straight leg portion arranged parallel with the aforementioned straight leg portion and used therewith for inside measurements, means for simultaneously adjusting the members of said pair, means for independently adjusting the leg portion of said additional member toward and away from the first mentioned straight leg portion, and means for determining the degree of the last named adjustment.

2. A device of the class described comprising a pair of pivotally connected members, and an additional member pivotally associated with the aforementioned members, one of the members of said pair having graduations thereon, said additional member having graduations thereon, the other member of said pair having indicating characters to cooperate with said graduations to provide for a reading of the device, said

members at one end of the device being designed to be used for inside measurements, said members at the other end of the device being used for outside measurements, means for adjusting the pair of said members relatively, and means for adjusting the additional member independently of said pair of members for the purpose specified.

3. A device of the character described comprising a pair of pivotally connected members, each including a curved leg portion, the latter being used together for outside measurements, one of said members including a straight leg portion, said last mentioned member having graduations on both sides, the other of said members having indicating characters adapted to cooperate with said graduations, an extension formed on the second mentioned member and having graduations thereon, an additional member pivotally associated with the first mentioned member, and including a straight leg portion arranged parallel with the aforementioned straight leg portion and used with the latter for inside measurements, said additional member having an indicating character cooperating with the adjacent graduations of the first mentioned member, means for simultaneously adjusting the members of said pair, said additional member including an obliquely disposed portion terminating in a point and movable over said graduated extension, adjustable means connecting said obliquely disposed portion with said extension, whereby said leg of the additional member is substantially of independent adjustment toward and away from the first mentioned straight leg portion for the purpose specified.

In testimony whereof I affix my signature.
RAFAEL M. ROBLES.
